HEAT SEALING MACHINE

Kermitt H. Cooper, New Rochelle, N.Y., assignor to
Engineered Packaging Associates, New Rochelle, N.Y.,
a firm

Filed Apr. 15, 1964, Ser. No. 79,499

Term of patent 14 years

(Cl. D55—1)

FIG.1

FIG. 2

FIG. 1 is a perspective view of a heat sealing machine, showing my design; and

FIG. 2 is a perspective view as seen upon rotation of the machine through an angle of approximately 180 degrees.

I claim:

The ornamental design for a heat sealing machine, as shown.
